UNITED STATES PATENT OFFICE.

HERMANN LOHSE, OF KNOXVILLE, PENNSYLVANIA, ASSIGNOR OF ONE-FOURTH TO CARL H. ENGELMOHR, OF PITTSBURG, PENNSYLVANIA.

ICE-CREAM FREEZER.

SPECIFICATION forming part of Letters Patent No. 773,512, dated October 25, 1904.

Application filed July 29, 1904. Serial No. 218,684. (No model.)

To all whom it may concern:

Be it known that I, HERMANN LOHSE, a citizen of the United States of America, residing at Knoxville borough, in the county of Allegheny and State of Pennsylvania, have invented certain new and useful Improvements in Ice-Cream Freezers, of which the following is a specification, reference being had therein to the accompanying drawings.

10 This invention has relation to ice-cream freezers and shipping-tubs, and has for its object the provision of novel means whereby the ice-cream can, which is located within the shipping-tub, can be thoroughly packed to 15 serve the character and quality of the cream contained within the ice-cream can.

My invention further resides in providing novel means for packing the ice contained within the tub and removing the water therefrom; and the invention further contemplates 20 constructing an attachment for freezing-cans and shipping-tubs which will embody particular features from which the results enumerated above may be obtained.

25 Briefly described, my invention consists of a cylindrical casing which is adapted to fit over the freezing-can and close the space which exists between the shipping-tub and the can, and I have provided the casing with a suitable 30 cover or lid having formed therein peep-holes, whereby the condition of the ice may be from time to time observed.

The above construction will be more fully described and then specifically pointed out in 35 the claims, and referring to the drawings accompanying this application, Figure 1 is a vertical sectional view of the shipping-tub, showing my improvement mounted therein. Fig. 2 is a vertical sectional view of the same. 40 Fig. 3 is a top plan view of a shipping-tub, showing my improvement mounted therein; and Fig. 4 is a transverse sectional view taken on the line *xx* of Fig. 2.

In the several views of the drawings accompanying this application like numerals of reference designate corresponding parts, and the reference-numeral 1 designates a shipping or packing tub which is of the ordinary and well-known construction, and in this tub is cen-

trally located a freezing or packing can 2. 5° My invention resides in providing a sleeve 3, which is slidably mounted upon the freezing or packing can 2, and secured to the periphery of this sleeve 3 is an annular shell which consists of the vertical sides 4, the top 5, and the bottom 6. The top and bottom of the annular shell are flanged, as indicated at 7, whereby the same may be soldered or otherwise secured to the sleeve 3, this sleeve being made of a sufficient length to slightly project 6° above the top flange 7 of the shell, whereby a lid or cover may be secured thereon. The lid or cover consists of an annular shell 8, having a bottom 9 formed therein, and in the top of the shell 8 is soldered or otherwise secured a flanged top 10, forming a receptacle between said top and the bottom 9. The bottom 6 of the shell, which fits within the shipping or packing tub, is provided with an aperture 11, in which a suitable pipe 12 is placed, 7° and the top 5 of this same shell is provided with a suitable opening 14, and a pivoted gate or lid 15 is mounted upon the top 5, whereby the opening 14 may be closed when so desired. The top 10 of the lid or cover is also provided 75 with an opening 16, and a suitable gate or cover 17 is pivoted to the top 10, whereby this opening may be closed at any time it is desired.

It will thus be seen that my invention resides in the provision of a novel attachment which may be readily used upon shipping or packing tubs and cans of the ordinary construction, and the manner of using this improved attachment is as follows: We will assume that the frozen ice-cream is packed within the can 2 and it be desired to preserve or keep the same for a long period of time. The space 18, which exists in the bottom of the tub, is filled with ice, the ice surrounding the 90 can 2 containing the cream and maintaining a low degree of temperature in this compartment. Ice is then placed in the shell formed by the top 5, the bottom 6, and the sides 4, the ice being placed therein through the opening 14. Ice is also placed within the lid 8, the ice being placed through the opening 16 into the space which exists between the bot-

tom 9 and the top 10, which form the lid. Ice or a suitable freezing agent having been placed in its respective compartments, the attachment is adapted to maintain the position 5 it assumes within the shipping or packing tub until some of the ice has become melted or disintegrated, at which time the attachment will gradually sink to the position shown in dotted lines in Fig. 2. Upon the ice becoming 10 melted in the larger compartments surrounding the sleeve 3 more ice may be admitted to this compartment through the opening 14, and what water that may accumulate within said compartment may be removed by 15 the pipe 12.

From the above it will be seen that a quantity of ice may be stored within the shipping or packing tub, whereby as the same melts or becomes disintegrated the cream within 20 the freezing or packing can 2 will be at all times kept in a cool state, owing to ice continually surrounding the same.

While I have herein shown the preferred manner of constructing my improvement for 25 ice-cream cans and shipping-tubs, I desire it to be understood that I do not care to limit myself to this specific construction, but may depart therefrom, as will be permitted by the scope of the appended claims.

30 What I claim, and desire to secure by Letters Patent, is—

1. The combination with a packing-can and

an ice-receptacle surrounding the can and removably mounted thereon, said receptacle having a closed bottom and a top, the latter being 35 provided with means for introducing ice into the receptacle, of a cover removably mounted on the said receptacle, said cover having a closed bottom, and a top, the latter being provided with means for introducing ice into the 40 cover.

2. The combination with a tub and a packing-can, of a hollow receptacle slidably mounted upon said packing-can, said receptacle having an opening formed therein, a hollow lid 45 adapted to fit over said receptacle and said packing-can, said hollow lid having an opening formed therein, and means for closing said openings, substantially as described.

3. The combination with a tub and a packing-can, of a sleeve slidably mounted upon said packing-can, a cylindrical shell secured to said sleeve, said shell having an opening formed therein, a hollow lid adapted to fit over said sleeve, said lid having an opening formed 50 therein, and means for closing said openings, substantially as described.

In testimony whereof I affix my signature in the presence of two witnesses.

HERMANN LOHSE.
